(57) **CLAIM**

The ornamental design for an altitude increasing connector, as shown and described.

DESCRIPTION

FIG. 1 is a perspective view of an altitude increasing connector showing the new design;

FIG. 2 is a front view of an altitude increasing connector showing the new design;

FIG. 3 is a rear view of an altitude increasing connector showing the new design;

FIG. 4 is a left side elevational view of an altitude increasing connector showing the new design;

FIG. 5 is a right side elevational view of an altitude increasing connector showing the new design;

FIG. 6 is a top view of an altitude increasing connector showing the new design; and,

FIG. 7 is a bottom view of an altitude increasing connector showing the new design.

The broken lines in the drawing depict environmental subject matter only and form no part of the claimed design.
